CASING SCRAPER

Cicero C. Brown, Houston, Tex.

Application August 16, 1951, Serial No. 242,113

5 Claims. (Cl. 166—173)

1

This invention relates to an improved scraping tool for well pipes.

Such tools, commonly called casing scrapers, are employed in oil well operations for scraping the inner wall of a well pipe or casing in order to remove scale, dirt, cement, and various other types of deposits and projections from the pipe wall in order to provide a smooth surface for seating packers, plugs and other types of well tools which are conventionally employed to form a fluid-tight seal with the pipe wall. Due to the high pressures which must frequently be sealed off, it is obviously of greatest importance that the seat formed by the pipe wall be as smooth as possible in order that the sealing tool will seat with maximum sealing efficiency against the pipe wall throughout the seating area. Also, the scrapers may be employed to clean the casing surface from its upper end down to the seating area in order to remove any projections which might tend to tear or damage the sealing element of the packer or plug as it is lowered through the casing, since such sealing elements are ordinarily constructed of relative soft materials such as rubber or the like.

The present invention has for its principal object the provision of an improved form of scraping tool which operates with maximum scraping efficiency throughout the entire circumferential area of the pipe wall.

An important object is the provision of a scraping tool employing a combination of spring and hydraulic pressure to force the scraping elements against the pipe wall.

A more specific object is the provision of a tool employing a plurality of pairs of radially expandible segmental scraping elements arranged on opposite sides of the tool body, the pairs being oriented about the longitudinal axis of the tool with respect to each other to cover the entire circumference of the pipe wall being scraped thereby.

Other and more specific objects and advantages of the present invention will become apparent from the following detailed description when read in conjunction with the accompanying drawings which illustrate one useful embodiment in accordance with this invention.

In the drawings:

Fig. 1 is a longitudinal, partly sectional view of the scraping tool;

Fig. 2 is an elevational view of the body of the scraping tool;

Fig. 3 is a cross-sectional view along line 3—3 of Fig. 2;

Fig. 4 is a cross-sectional view along line 4—4 of Fig. 2;

Fig. 5 is an enlarged, generally quarter-sectional, view of the principal portions of the assembled tool;

2

Fig. 6 is a cross-sectional view along line 6—6 of Fig. 5; and

Fig. 7 is a cross-sectional view along line 7—7 of Fig. 5.

Referring to Fig. 1 of the drawings, the scraping tool, indicated generally by the numeral 10 is shown inserted in a well casing C to be scraped thereby. The tool includes a body portion, designated generally by the numeral 11, having a diameter such that it may be inserted into casing C with a small amount of clearance. Body 11 is provided at its upper end with an integral elongated shank portion 12 of substantially smaller diameter than body 11. The upper end of shank portion 12 is provided with an externally threaded pin 13 and body 11 is provided at its lower end with an internally threaded socket 14. Pin 13 and socket 14 provides means by which the tool may be connected between sections of a pipe string 15 by which the tool may be lowered into casing C and operated therein. Body 11 has an axial bore 16 extending entirely therethrough and communicating with bore 17 of pipe string, whereby hydraulic fluid may be conducted from the surface through the tool, for purposes to be described hereinafter.

As shown particularly in Figs. 2, 3 and 4, body 11, adjacent the point of connection of shank portion 12, is provided with external threads 18 and the lower portion of body 11 adjacent socket 14 is provided with a second set of external threads 19. Intermediate the threaded portions 18 and 19, body 11 is provided with longitudinally spaced upper and lower slip-supporting sections 20 and 21, respectively, which are separated by an intermediate slip-retainer section 22.

Each of the slip-supporting sections 20 and 21 is provided on diametrically opposite sides thereof with a pair of elongated generally rectangular slots 23—23 which are cut into the exterior cylindrical surfaces of the sections over a width slightly less than the diameter of the sections to thereby form a pair of laterally spaced outwardly extending flanges 24—24 along the sides of each slot. The slots in one of the sections are oriented at an angle of 90° with respect to the slots in the other section. The slots in section 20 extend longitudinally from threaded portion 18 at its upper end to retainer section 22 at its lower end, and the slots in section 21 extend from retainer section 22 at its upper end to threaded portion 19 at its lower end. The lower end of threaded section 18 thereby forms a downwardly facing shoulder 25 extending over the upper ends of the slots in section 20 and the upper end of retainer section 22 forms an upwardly facing shoulder 26 extending over the lower end of these slots. Similarly, the lower end of retainer section 22 forms a downwardly facing shoulder 27 over the upper ends of the slots in section 21 and

the upper end of threaded section 19 forms an upwardly facing shoulder 28 extending over the lower ends of the slots in section 21. The upper and lower ends of flanges 24 are cut away to provide narrow annular clearance spaces between the ends of the flanges and the respective above-mentioned adjacent shoulders.

In removing metal to form slots 23, a portion is left medially of the slot to form a generally rectangular boss 29 equi-distantly spaced from side flanges 24-24 and extending radially outwardly from the bottom wall 30 of the slot to a point approximately flush with the outer ends of slots 24-24. Boss 29 is made slightly shorter longitudinally than flanges 24-24, the ends of the boss being equi-distant from the adjacent ends of the flanges. A plurality of longitudinally spaced cylinders 31-31 are provided in boss 29, extending inwardly from the outer face thereof and communicating at their inner ends with bore 16 through fluid passageways 32. A small cylindrical piston 33 fitted with sealing rings 33a is reciprocably mounted in each of the cylinders 31.

A scraper slip 34 is mounted in each of the slots 23 for radial movement therein. Slip 34 is generally rectangular in shape to provide free sliding fit in slot 23. The outer face of the slip is arcuate having approximately the same radius as body 11. The inner face of the slip is flat and is provided medially with a rectangular recess 35 registering with, and adapted to slidably receive, boss 29. On each side of recess 35 there is provided a plurality of longitudinally spaced cylindrical recesses 36, each adapted to receive one end of a coil compression spring 37, the other end of which bears against bottom wall 30 of slot 23, springs 37 normally tending to urge the slip outwardly of slot 23. A plurality of spaced scraping teeth 38 are formed on the exterior of slip 34, being preferably in the form of segments of a coarse helical thread having a generally square cross section so that the upper and lower edges of the thread segments form sharp scraping edges 39-39 extending slopingly across the face of the slip. The outer face of the slip is cut back at its upper and lower ends to form upwardly and downwardly facing external portions 40 and 41, respectively, of reduced thickness.

An elongated tubular sleeve 42 surrounds shank portion 12 and is internally threaded at its lower end to screw down over threads 18, the lower end of sleeve 42 forming an annular flange 43 which projects below shoulder 25 and over reduced portions 40 of the slips to serve as a retainer for the upper ends of the slips which are mounted in the slots in section 20, while permitting a limited amount of radial outward movement of the slips. The upper end of sleeve 42 is open, forming a trap for detritus which may settle out of fluid flowing up past the outside of the tool during operation of the tool. A plurality of drain holes 44 are provided through the wall of sleeve 42 just above the point of connection of the sleeve to threads 18. One or more set screws, as shown, extends through the threaded portion of sleeve 42 to firmly lock the sleeve to body 11.

A short internally threaded sleeve 46 is mounted over the lower end of body 11 and is adapted to be screwed upwardly on threads 19 and is provided with an annular flange 47 projecting upwardly above threads 19 and is designed to surround the cut back portions 41 at the lower ends of the slips mounted in the slots in section 21 to serve as retainers therefor.

functioning in this respect similarly to flange 43 of sleeve 42. One or more set screws 48 are employed to lock sleeve 46 firmly to body 11.

Retainer section 22 has its exterior machined to form a square. Each face of the square is provided with transverse dove-tail groove 49, the sides of the groove tapering slightly toward one end, as best seen in Fig. 2. A square keeper plate 50 is provided for attachment to each face of the retainer section. A dove-tail tongue 51 is provided on the inner face of each keeper plate 50 and is tapered from end-to-end to complement groove 49. Tongue 51 extends transversely across the plate and projects slightly from opposite sides thereof. With this construction it will be seen that the keeper plates may be pushed into place successively around the four faces of the retainer section and each will not only be locked to its respective face of the retainer section but will over-lap the end of the next succeeding plate and will thereby lock each other against lateral dislodgement from the faces of the retainer section. Each of the keeper plates is provided in the center thereof with a hole 52 which is tapped on its inner end to receive a set screw 53, such as a conventional "Allen-Head" screw, which may be employed to additionally hold the keeper plates in place, after they have been properly assembled, by inserting a wrench through the outer ends of holes 52 in order to turn the screws 53. Each of the keeper plates projects above and below shoulders 25 and 27 and the projecting portions are provided on their inner faces with horizontal rectangular recesses 54 which are designed to receive the cut back portions of the slips adjacent the upper and lower ends of retainer section 22 to thereby form retainers for these ends of the slips while permitting the desired degree of limited radial movement of the slips.

The scraping tool, constructed as described above, is operated in the following manner:

The tool, connected into the string of operating pipe 15, is lowered through the upper end of casing C to the section of the inner surface of the casing which is to be scraped or cleaned. The pressure of coil springs 37 will urge slips 34 outwardly against the casing surface so that teeth 38 will be held in scraping engagement with the casing surface and by reciprocating operating pipe 15 longitudinally along the section to be scraped, the edges 39 of the teeth will act to scrape the surface of this section of the casing. However, the scale, cement, or other projections on the casing wall which it is sought to thus remove, is often sufficiently hard and resistant in character, so that the outward pressure of coil springs 37 on slips 34 will be overcome and the scraping teeth will merely slide over the surface of the material which it is desired to remove without effectively scraping this material from the casing wall. To obviate this undesirable condition, a suitable hydraulic fluid, such as water, drilling mud, or the like, is pumped downwardly through the bore 17 of operating pipe 15 and bore 16 of the scraping tool and circulated in a generally conventional manner through a suitable opening in the lower end of the pipe string and up outside the string through the annular space between the tool and casing C. The pressure of this circulating fluid will be exerted through passageways 32 against the inner ends of pistons 33 and will force these pistons outwardly of cylinders 31 against the inner faces of slips 34 driving the latter outwardly against the casing wall and thereby supplementing the force of springs 37.

The combination of spring and hydraulic pressure thus exerted on slips 34 may be adjusted by suitable control of the hydraulic pressure to assure effective scraping of the inner surface of casing C as the tool is reciprocated in the casing. As the hydraulic fluid flows upwardly past the outside of the tool, any detritus constituting the scrapings which tends to settle out of the fluid will deposit in the annular space between sleeve 42 and shank portion 12, thereby preventing such detritus from falling back between the casing wall and the scraping elements. Liquid collecting in the bottom of sleeve 42 will drain back into the casing through drain holes 44.

By providing at least two sets of scraping slips, angularly oriented with respect to each other as previously described, scraping of the entire circumferential area of casing C will be effectively accomplished. It will be understood that more than two sets of scraping slips may be employed and suitably angularly oriented with respect to each other about the longitudinal axis of the tool to accomplish this purpose.

It will be obvious that instead of scraping only a relatively short section of the casing, the entire length of the casing down to the point at which a sealing tool is to be set may be scraped. This may be accomplished by initiating the reciprocating scraping movement when the tool first enters the casing and continuing this movement while the tool is being lowered through the casing down to the point at which the sealing tool is to be set. In this way, the inner wall of the casing may be smoothed all the way down to the sealing area and this will obviate tearing or abrasion of the sealing elements when the sealing tool is subsequently lowered through the casing.

It will be understood that numerous modifications and changes may be made in the details of the illustrative embodiment within the scope of the appended claims without departing from the spirit of this invention.

What I claim and desire to secure by Letters Patent is:

1. A casing scraper, comprising, a tubular body insertible in a casing and having an axial bore therethrough, a plurality of circumferentially spaced longitudinally extending slots in the exterior of said body, arcuate scraping elements mounted in said slots for radial movement therein, means on the body limiting outward movement of the scraping elements in the slots, hollow bosses projecting radially from the bottom of said slots intermediate the sides of the slots and communicating with said axial bore, resilient means mounted on opposite sides of said bosses in compression between the bottoms of said slots and said scraping elements to normally urge said scraping elements outwardly into scraping engagement with the wall of said casing, and radially slidible pistons mounted in said bosses and having their outer ends thrustingly engageable with the inner faces of said scraping elements, said pistons being actuatable by hydraulic pressure within said bore to intensify the outward force on said scraping elements.

2. A casing scraper, comprising, a tubular body insertible in a casing, a plurality of longitudinally spaced pairs of slots in the exterior of said body, arcuate scraping elements mounted in said slots for radial movement therein, means mounted on the body limiting outward movement of the scraping elements in the slots, the members of each of said pairs of slots and related scraping

elements being disposed on diametrically opposite sides of said body, and said pairs of slots and related scraping elements being angularly oriented with respect to each other about the longitudinal axis of said body whereby said scraping elements together when moved outwardly will engage substantially the entire circumference of the wall of said casing, hollow bosses projecting radially from the bottoms of said slots intermediate the sides of the slots and communicating with the interior of the body, recesses in the inner faces of the scraping elements slidably receiving said bosses, resilient means mounted in compression between the bottoms of the slots and said scraping elements to normally urge said scraping elements outwardly into scraping engagement with the wall of said casing, and means including radially slidible pistons in said bosses actuatable by hydraulic pressure from within said body to intensify the outward force on said scraping elements.

3. A casing scraper, comprising, a tubular body insertible in a casing and having an axial bore therethrough, a plurality of longitudinally spaced pairs of slots in the exterior of said body, arcuate scraping elements mounted in each of said slots for radial movement therein, means mounted on the body limiting outward movement of the scraping elements in the slots, the members of each of said pairs of slots and their related scraping elements being disposed on diametrically opposite sides of said body, and said pairs of slots and related scraping elements being angularly oriented with respect to each other about the longitudinal axis of said body whereby said scraping elements together when moved outwardly will engage substantially the entire circumference of the wall of said casing, hollow bosses projecting radially from the bottoms of said slots intermediate the sides of the slots and communicating with said axial bore, recesses in the inner faces of the scraping elements slidably receiving said bosses, resilient means mounted on opposite sides of said bosses in compression between the bottoms of the slots and said scraping elements to normally urge said scraping elements outwardly into scraping engagement with the wall of said casing, and radially slidible pistons mounted in said bosses and having their outer ends engageable with the inner faces of said scraping elements, said pistons being actuatable by hydraulic pressure within said bore to intensify the outward force on said scraping elements.

4. A casing scraper according to claim 3 having keeper elements mounted on said body and engaging the opposite ends of said scraping elements to limit their outward movement in said slots.

5. A casing scraper according to claim 3 wherein said scraping elements are provided on their exterior faces with scraping teeth comprising segments of a helical thread formed thereon.
